DIAPHRAGMETER

Daniel William Powell, Jr., Baltimore, Md.

Application May 20, 1939, Serial No. 274,824

1 Claim. (Cl. 128—2.08)

The diaphragmeter is an apparatus consisting of a rubber bag having an intake rubber tube attached and an outlet pressure tube attached as one unit. The intake tube has a rubber bulb or pump attached having a check valve on it for the purpose of inflating said bag or sack and retaining the inflation of same to any given number of degrees of pressure to be indicated on a pressure gauge. The outlet pressure tube is operatively connected to said gauge, preferably a mercury gauge marked in a scale of degrees for the purpose of indicating the differential pressures transmitted from the bag or sack. The gauge is constructed with a rubber base which when placed on a flat surface such as a piano top creates a partial vacuum thus causing a suction which will hold the gauge securely in an upright position and will not mar or scratch said surface. The rubber bag is of a shape and size that will readily conform to the individual shapes of human bodies in the region adjacent to the diaphragm muscle. The rubber bag or sack is covered with leather or a suitable material which will have a face such as the one herein described made from treated oak leather with straps sewed or secured to the tips, the shape of which conforms to the shape of the rubber bag or sack, the back of the cover is made from a softer leather or suitable material, and in this one calf-skin is used. This back is also cut the same shape as the heavier face but somewhat larger in dimensions so that when it is sewed or secured to the face with the bag or sack inside the cover thus formed, is somewhat larger than the bag or sack and allows same room to expand when the bag or sack is inflated but retains the bag or sack to its shape and keeps it from bulging or expanding further when any physical force is brought to bear on the cover, thus creating a differential of degrees to be transmitted to the pressure gauge when a physical action such as the diaphragm muscle makes in the act of singing and speaking correctly is brought to bear on the back of the cover strapped on an individual's body so that the back of the cover is in contact with the region of the body adjacent to the diaphragm muscle. The various actions of the person's diaphragm muscle from the instant of inhalation, the action made by it in the attack of a tone, and the subsequent further actions made in singing a sustained tone or a succession of tones such as a scale or a musical phrase in a song or aria will all take place against the back of the covered bag when strapped in place on the body stated above thus creating differen-

tial pressures in the bag which being transmitted to the pressure gauge marked in a scale or degrees will be indicated on the gauge in accordance with each action the muscle makes in the various acts of singing or speaking with the correct use of the diaphragm muscle. This diaphragmeter affords to my knowledge the first means of registering the all important actions of the diaphragm muscle, giving the pupil and instructor the means of keeping a chart for reference purposes by noting the different actions of the muscle, to which it is put to use for the right technic of singing beautiful resonant tones. Through many years of study and vocal training I have learned the proper use of the diaphragm muscle is the only means by which an individual can sing or speak in a beautiful tone so I am sure this diaphragmeter will prove invaluable to the instructor and individual interested in this art.

The accompanying drawing shows diagrammatically the diaphragmeter in its entirety in the proper place on the human torso with numerals indicating its various parts.

1 is the face or outside of the cover made of treated oak leather or such material as will be flexible and yet be heavy enough so the rubber bag or sack it faces will resist any outside physical action brought to bear on the inflated rubber bag or sack. The shape is such that it is the same as the bag or sack but cut slightly larger. 25
1 has strap 5 with a buckle attached, sewed, or secured to one tip and strap 4 with eyelets conveniently spaced, sewed, or secured to the opposite tip. These straps 4 and 5 are of a convenient length and strength so as to meet with the various girths of the individual bodies to which the covered bag or sack is strapped. 2 is the rubber bag or sack made of an inflatable material, in this instance rubber of a gauge that will lend itself to easy inflation, and shaped so that when 30 in the like shaped cover will conform to the shape of the region of the human body adjacent to the diaphragm muscle. 2 has the intake rubber tube 6 attached, having the rubber bulb or pump 8 with the check valve 7 attached for the purpose of inflating the bag 2 and retaining the inflation to a given number of degrees to be indicated on the gauge. The rubber bag 2 also has the outlet pressure tube 9 attached and the connection 10 which fits into connection 11 35 thus completing the outlet pressure tube which transmits pressure in the bag 2 to the pressure gauge attached to same at connection 13. The dotted lines in the drawing show the straps going around the body and buckled at the back. 50
55

14 is the diaphragm in the mercury reservoir 15 which prevents the mercury from backing up into the outlet pressure tube 3 but when any pressure is transmitted to 14 it responds and 5 forces the mercury to rise in the glass tube 20 marked in a scale of degrees, thus indicating the amount of pressure. 18 and 22 are the appliances which hold the glass tube 20 to its support 19. 21 is the mercury shown in the base 10 of the glass tube 20. 16 shows the metal base to which the rubber suction cup 17 is attached which suction cup forms a partial vacuum when in contact with a flat surface, thus creating a 15 suction which holds the gauge in an upright position but does not mar or scratch the surface to which it is attached.

When the covered rubber bag or sack is strapped around the region of the body adjacent to the diaphragm muscle shown by numeral 12 20 the bag or sack 2 is inflated in its cover, the back of which contacts the region of the body adjacent to the diaphragm muscle. Now for example, if the rubber bag or sack 2 is inflated so that 10 degrees is indicated on the pressure 25 gauge this pressure is maintained throughout the lesson or singing period by closing the check valve 7, thus enabling the instructor and pupil to make all calculations from 10 degrees or if a higher degree to start with is preferable, that 30 can be done in the same way as shown above. The individual on whom the diaphragmeter is strapped is then told to inhale which when done correctly for the purpose of singing or speaking correctly the physical action of the diaphragm 35 muscle thus resulting takes place against the back of the cover 3. This resulting physical action causes the mercury in the gauge to rise from the given number of degrees started with to a greater number of degrees in accordance with the amount 40 of physical action the individual's diaphragm is capable of making. The differential pressure brought about by the physical action of the diaphragm muscle on the inflated bag will be indi-

cated in degrees on the gauge accordingly. The further action of this muscle in the attack of the tone and the manner in which it is used to sustain tones or sing a succession of tones in a scale or musical phrase also taking place against the 5 back of the cover will relatively be indicated in degrees on the gauge. While an individual is singing or speaking correctly the diaphragm muscle is constantly in action and since it is very important that this muscle be used correctly to 10 attain the best tones possible, the person and instructor can keep a chart from day to day of its action on individuals which will be an invaluable source of permanent reference and show just what, if any, progress is being made in the 15 perfection of the use of this all important muscle.

I claim:

In a diaphragmeter, an elongated inflatable bag adapted to contact the human body over the diaphragm muscle, an enclosing cover or relatively stiff leather for retaining said bag in a desired shape and size after inflation of said bag, said bag and cover each being of a shape and size to overlie substantially the entire diaphragm muscle, adjustable straps secured to the respective ends of said cover, and extending around the human body for securing said bag and cover over the diaphragm muscle, means for inflating said bag, a check valve associated with said inflating means to maintain said bag inflated to a desired degree of inflation, an outlet conduit leading from said bag to a pressure indicating means, and a detachable connection in said conduit, said pressure indicating means including a cylinder, a movable means operative in said cylinder to transmit pressure indications from said conduit, said movable means transmitting said indications to a pressure gauge, whereby the variations in pressure in said conduit resulting from the expansion and contraction of the diaphragm may be transmitted to and indicated upon said gauge. 30 35 40
